UNITED STATES PATENT OFFICE.

CHARLES PLACE, OF CAMBRIDGE, MASSACHUSETTS.

DESIGN FOR A JEWELRY-RACK.

SPECIFICATION forming part of Design No. 16,556, dated March 2, 1886.

Application filed January 19, 1886. Serial No. 189,109. Term of patent 14 years.

To all whom it may concern:

Be it known that I, CHARLES PLACE, a citizen of Canada, residing at Cambridge, in the county of Middlesex and State of Massachusetts, have invented a certain new and useful Design in Jewelry-Racks; and I do hereby declare the following to be a full, clear, and exact description of the invention, such as will enable others skilled in the art to which it applies to make and use the same.

My invention relates to a new and original design in jewel-racks or display-cards.

In the accompanying drawing the figure shown is a view in perspective of my rack, showing the jewelry displayed thereon.

My design consists in a shoe having its side presented to view, and below the heel and sole thereof a longitudinal strip representing a foot-plate of a skate, the said plate having two disks at the bottom thereof, intended to represent rollers.

In the drawing, *a* represents the side view of a shoe, and *c* represents the foot-plate of

the skate, having the upwardly-curved forward and rear ends, *d*.

d' represents the disks at the bottom of the skate, and representing rollers, the same being centrally provided with the ornamental heads *e*.

Having fully described my invention, what I claim as new, and desire to secure by Letters Patent, is—

The design for a jewel-rack herein shown and described, the same consisting of the back having the conventional outline of a shoe standing above the foot-plate, which is provided upon the lower edge with circular disks, as set forth.

In testimony whereof I have signed this specification in the presence of two subscribing witnesses.

CHARLES PLACE.
